UNITED STATES PATENT OFFICE

JOHN T. HUME, OF CHICAGO, ILLINOIS, ASSIGNOR TO ELECTRIC HOUSEHOLD UTILITIES CORPORATION, OF CICERO, ILLINOIS, A CORPORATION OF ILLINOIS

DESIGN FOR A COMBINED WASHING MACHINE CASING AND WRINGER

Application filed March 14, 1931. Serial No. 39,080. Term of patent 14 years.

To all whom it may concern:

Be it known that I, JOHN T. HUME, a citizen of the United States, resident of Chicago, in the County of Cook, State of Illinois, have invented a new, original, and ornamental Design for a Combined Washing Machine Casing and Wringer, of which the following is a specification, reference being had to the accompanying drawing, forming part thereof.

The figure is a perspective view of a combined washing machine casing and wringer, showing my new design.

I claim:

The ornamental design for a combined washing machine casing and wringer as shown.

JOHN T. HUME.
